(Cl. D45—4)

To all whom it may concern:

Be it known that I, Michael Chernow, a citizen of the United States, and residing at New York, in the county of New York and State of New York, have invented a new, original, and ornamental Design for a Link Chain for a Bracelet or the like, of which the following is a specification, reference being had to the accompanying drawings, forming part thereof, and in which

Fig. 1 is a top plan view of a link chain, showing my new design,

The characteristic feature of my design for a link chain for a bracelet resides in the multiple plate upstanding links of the configuration shown,
